(57) **CLAIM**

We claim the ornamental design for paint spreader, as shown.

DESCRIPTION

FIG. 1 is a first side view of a paint spreader according to the present invention.

FIG. 2 is a back view of the paint spreader.

FIG. 3 is a front view of the paint spreader.

FIG. 4 is a second side view of the paint spreader.

FIG. 5 is a bottom view of the paint spreader; and,

FIG. 6 is a top view of the paint spreader.

The broken line showing of a paint can is for illustrative purposes only and forms no part of the claimed design.
